UNITED STATES PATENT OFFICE

2,444,220

ENGINE CYLINDER FIN AND BAFFLE
CONSTRUCTIONAllan P. Colburn, Newark, Del., assignor to United
Aircraft Corporation, East Hartford, Conn., a
corporation of Delaware

Application September 30, 1944, Serial No. 556,561

2 Claims. (Cl. 257—261)

1

This invention relates to a heat exchange structure and particularly to a heat radiating structure and enclosing baffle for cooling aircraft engine cylinders.

A primary object of the invention is to provide an improved metal fin and baffle construction that will enable a cylinder, or other member, to be cooled uniformly circumferentially and which will have maximum cooling effect over the entire surface of the cylinder barrel or other member with minimum air drag.

Another object of the invention is to improve the cooling effect of a fin and baffle construction surrounding a cylinder in which the baffle has a single opening for admitting air to the interfin spaces and preferably has groups of separate exit openings alternately circumferentially spaced for individual or for several adjacent interfin spaces.

A still further object of the invention is to provide an air-cooled engine cylinder having intermediate cut-away fins alternating with complete annular fins, in which the alternate intermediate fins have their cut-away portions displaced circumferentially.

Another object is to arrange alternating, complete and cut-away fins within a baffle having circumferentially displaced exhaust openings in a manner to equalize the flow velocity or frictional resistance within the interfin spaces served by a single exhaust opening so that the longer path about the cylinder for air passing between adjacent complete annular fins may have the same air resistance as the shorter path about the cylinder, substantially all of the cut-away portions of the intermediate fins being disposed within the longer air passages.

Another object of importance is to increase the fin area surrounding the trailing half of the cylinder, the full diameter portions of the cut-away fins being disposed to surround the trailing portions of the cylinder while their cut-away portions are disposed to surround the leading half of the cylinder, also with the increased fin area in the trailing half, the velocity of the air mass within the trailing half is increased.

This application is a companion case to the application of Donald S. Hersey U. S. application Serial No. 556,563, filed September 30, 1944, now abandoned, for Engine cylinder baffle, and represents an improvement and development thereon.

Other objects and advantages will be apparent from the specification and claims and from the drawing which illustrates what is now considered to be a preferred embodiment of the invention.

In the drawing, Fig. 1 is a front elevation of a

portion of a cylinder provided with the baffle and fin structure forming the present invention.

Fig. 2 is a rear elevation of the portion of the cylinder and cooling structure shown in Fig. 1.

Fig. 3 is a plan view of the parts shown in Fig. 1.

Fig. 4 is a central longitudinal section of the cylinder and cooling structure taken on the plane of line 4—4 in Fig. 3.

Fig. 5 is a plan view of one of the intermediate 10 partially cut-away annular fins, and

Fig. 6 is a horizontal sectional view taken on the plane of line 6—6 in Fig. 1, and showing one of the partially cut-away fins in position within the baffle.

16 In its preferred form, the invention may include the following principal parts: First, a cylinder barrel or other member having relatively widely spaced annular fins thermally united to the external surface of the cylinder walls; second, 20 a baffle partially surrounding and enclosing these fins and preferably being thermally united thereto; third, separate alternately circumferentially spaced exhaust openings formed in the baffle for exhausting air from spaces between one or more 25 adjacent annular fins; and fourth, intermediate fins thermally united to the cylinder and having their outer periphery partially cut away, these fins being interposed between adjacent complete annular fins, the cut-away fins being disposed 30 with their cut-away portions alternately circumferentially spaced, and also so disposed that there is a maximum fin area in the trailing portions of the cylinder.

In cylinder cooling in which annular circumferential radially extending fins are employed, it is desirable to make equally efficient use of all portions of the surfaces of the fins to substantially 35 equally cool circumferentially all portions of the cylinder barrel. The front halves of the fins and cylinder are subject to air approaching the cylinder and accordingly are cooled to a maximum degree.

40 The trailing halves of the cylinder and fins, however, must have the air constrained to contact them so that the greatest possible mass flow of cooling air will contact the maximum area of their surfaces. For this purpose an enclosing baffle is placed about the cylinder, there being a single large opening for the admission of air on the leading side of the cylinder. At the

45 rear of the cylinder there preferably are provided separated circumferentially elongated exhaust openings formed in the baffle, each opening having a vertical height or axial width equal, 50 55 in the embodiment of the invention illustrated

in the drawing, to but two of the individual spaces between adjacent fins.

The exhaust openings in the baffle are alternately spaced circumferentially of the cylinder for spaces between adjacent complete annular fins. The cooling air, therefore, passing around the trailing half of the cylinder is maintained in contact with the surfaces of the fins by the enclosing baffle. A portion of the air passing through an interfin space is exhausted after passing a short distance circumferentially beyond the rear central portion of the cylinder. To further increase the efficiency of the cooling fins, intermediate partially cut-away fins are interposed midway within the spaces between adjacent complete annular fins served by a single exhaust opening.

Paths for the cooling air entering the interfin spaces served by a single exhaust opening are unequal in length depending upon the direction taken by the air in passing around the cylinder to the exit openings. Means, therefore, are provided to equalize the frictional resistance within these paths of unequal length so that substantially equal mass flows of air will occur in each path. For this purpose the interposed cut-away fins have their cut-away portions extending principally within the longer path, the portion of the interposed cut-away fin of full width extending substantially throughout the entire length of the shorter path. The longer path, within which the cut-away portion is disposed, therefore, has more free air space than the shorter path; this greater free air space in the longer path serving to equalize the mass flow through the two paths.

Also, in order that the maximum cooling area may be available over the trailing half of the cylinder, the full diameter portions of the cut-away fins are disposed so that they extend across the trailing half.

Referring more in detail to the figures of the drawing, I provide a cylinder 10, only a portion of which is shown in the drawing, with a plurality of circumferentially disposed radially extending fins alternately of two different types 11 and 12 extending radially outward from the outer wall of the cylinder and thermally united thereto in any preferred manner. Fins of type 11 are of uniform width throughout their entire circumference. Fins of type 12 are annular also but have a part of their outer peripheries cut away as shown in Fig. 5. Both types of fins are of metal, having high heat conducting qualities, preferably copper or aluminum.

Partially surrounding and enclosing cylinder 10 and fins 11 and 12 is a thin cylindrical baffle member 13 preferably thermally united to the outer edges of the fins. The front opening 14 of the baffle 13 for admitting air to the interfin spaces within the baffle 13 is relatively wide and preferably extends the full length of the portion of the cylinder 10 being cooled. In the trailing portion of the cylinder 10 are provided narrow circumferentially elongated slots or openings 15 in the baffle 13 forming exhaust openings for the air within separated interfin spaces. Exit openings 15 in the embodiment of the invention selected for illustration are spaced apart circumferentially of the cylinder 10 on either side of the central portion so that they are arranged in two circumferentially spaced groups. The openings 15 of each group are disposed in axial alignment.

Disposed centrally within the space between adjacent complete circumferential or annular fins

11 are fins of type 12 similar to that shown in Fig. 5 in which a large arcuate portion of the outer periphery has been cut away. These partially cut-away fins 12 are spaced midway between adjacent full annular fins 11. Preferably, and as shown, the spaces between these full annular fins 11 on either side of a cut-away fin 12 are served by a single exhaust slot or opening 15.

It will be noted from the above that air, entering the individual spaces between adjacent full circumferential fins 11 on either side of an intermediate partially cut-away fin 12, may pass around the cylinder 10 in either direction to an exit opening 15. In passing around the cylinder in one direction, the cooling air will have a much shorter path to the particular exhaust opening 15 for that section of the cylinder 10 than air passing around the cylinder in the opposite direction. This will be seen by an inspection of Fig. 6. In order to maintain equal frictional resistances in the two paths so that substantially equal air masses will flow in each direction, the partially cut-away intermediate fins 12 have substantially all of their cut-away portions disposed within the longer paths. There is, therefore, more free space for the cooling air within these longer paths. In the shorter paths, however, where the intermediate fins have their full width, the air has to pass within the restricted spaces on either side of the intermediate fin. The cooling air, therefore, in passing around the cylinder 10 through the longer path, will have a relatively free path for a major portion of its length and the air passing around the cylinder through the shorter path will have a more restricted path. Substantially equal mass flows of air will, therefore, occur in each path and the radiating surfaces in the two paths, therefore, will be substantially equally effective. Also as a portion of the cooling air passing around the trailing half of the cylinder 10 has to pass beyond the center of this half of the cylinder wall, the fin area adjacent this mid-portion of the trailing half of the cylinder 10 will be most effectively utilized.

Some of the advantages of using cut-away fins, as disclosed in this application, either with the exit openings 15 or with a single large exit opening corresponding to the inlet opening 14, are as follows: First, they provide more finned surface area in rear than in front; second, they reduce the resistance to the flow of cooling air; third, they decrease the weight of cylinder construction; fourth, they change the relative airflow resistance on opposite sides of the cylinder and cause the airstream on the side with the greater mass flow to flow across the rear of the cylinder and, thereby, effectively cool this portion of the cylinder. This effect of causing air to flow past the center of the trailing half of the cylinder is made to alternate from side to side by the provision of the two groups of circumferentially spaced exit openings 15.

In addition to increasing the airflow rate across the rear of the cylinder, because more air has come through the wider flow path, the trailing portion is more effectively cooled. Also there is a higher air velocity across the trailing half of the cylinder and for this reason the air contacting this trailing half of the cylinder is cooler.

It is to be understood that the invention is not limited to the specific embodiment herein illustrated and described, but may be used in other ways without departure from the spirit of the invention defined by the following claims.

I claim:

1. A cooling structure for cylinders comprising in combination, a cylinder barrel, a plurality of spaced annular fins surrounding said barrel, alternate fins having cut-away portions, said cut-away portions being spaced circumferentially of said barrel, and a baffle partially enclosing said barrel and fins and having circumferentially spaced exit openings for pairs of interfin spaces, said openings forming a longer and a shorter circumferential airflow path in each interfin space, and said cut-away portions of said fins being disposed in the longer path substantially to equalize airflow therein.

2. A cooling structure for cylinders comprising in combination, a cylinder barrel, a plurality of spaced annular fins surrounding said barrel, alternate fins having cut-away portions, said cut-away portions alternately spaced circumferentially of said barrel, and a baffle having a central front opening and partially enclosing said barrel and fins and having alternately circumferentially spaced exit openings for adjacent groups of inter-

fin spaces, and forming a longer and a shorter circumferential airflow path in each interfin space, and said cut-away portions of said fins being disposed in the longer path substantially to equalize airflow therein.
